(57) **CLAIM**

The ornamental design for a chair, substantially as shown and described.

DESCRIPTION

FIG. 1 is a perspective view of a first embodiment of my new design;

FIG. 2 is a side elevational view of the embodiment of FIG. 1, the opposite side view being a mirror image thereof;
FIG. 3 is a front elevational view of the embodiment of FIG. 1;

FIG. 4 is a rear elevational view of the embodiment of FIG. 1;

FIG. 5 is a top view of the embodiment of FIG. 1;
FIG. 6 is a perspective view of a second embodiment of my new design;

FIG. 7 is a side elevational view of the embodiment of FIG. 6, the opposite side view being a mirror image thereof;
FIG. 8 is a front elevational view of the embodiment of FIG. 6; and,

FIG. 9 is a rear elevational view of the embodiment of FIG. 6, the top view being identical to the top view for the first embodiment.

The fragmented pattern shown on the seat and backrest is
understood to represent fabric and would be continuous
throughout the circumscribed areas.
